US00D876271S

(12) **United States Design Patent** (10) Patent No.: **US D876,271 S**
(45) Date of Patent: **** Feb. 25, 2020**

(54) **BRACELET**

(71) Applicant: **MARCO BICEGO SpA**, Trissino (VI)
(IT)

(72) Inventor: **Marco Bicego**, Trissino (IT)

(73) Assignee: **Marco Bicego SPA**, Trissino (VI) (IT)

(**) Term: **15 Years**

(21) Appl. No.: **29/671,425**

(22) Filed: **Nov. 27, 2018**

(30) **Foreign Application Priority Data**

May 29, 2018 (EM) 005286960-0004

(51) **LOC (12) Cl.** **11-01**
